UNITED STATES PATENT OFFICE.

WILLIAM A. SMITH, OF DENVER, COLORADO, ASSIGNOR TO THE DENVER ROCK DRILL MANUFACTURING COMPANY, OF DENVER, COLORADO, A CORPORATION OF DELAWARE.

DRILL-SHARPENER.

1,233,723.

Specification of Letters Patent. Patented July 17, 1917.

Application filed September 27, 1916. Serial No. 122,526.

To all whom it may concern:

Be it known that I, WILLIAM A. SMITH, a citizen of the United States, residing at Denver, in the county of Denver and State 5 of Colorado, have invented certain new and useful Improvements in Drill-Sharpener, of which the following is a specification.

The present invention relates to drill sharpening apparatus, especially that type 10 employing motive fluid for actuating the elements.

It is the primary object of the present invention to provide a very compact and relatively simple apparatus that is entirely 15 practical, and while more especially useful for small plants, is of course not restricted to such use.

An embodiment of the invention is illustrated in the accompanying drawings, 20 wherein:—

Figure 1 is a side elevation of the apparatus, portions thereof being shown in section.

Fig. 2 is a rear elevation of the same.

Fig. 3 is a detail vertical sectional view through the controlling valve mechanism.

Fig. 4 is a detail elevation showing the disposition of the vise elements when said vise is closed.

Fig. 5 is a detail sectional view on the line 5—5 of Fig. 1.

Similar reference numerals designate corresponding parts in all the figures of the drawings.

In the embodiment disclosed, a base 8 is employed that may be supported on suitable legs 9, and is provided at one side of its center, and in effect in one corner, with an integral hollow standard 10 terminating in 30 ears 11. Fulcrumed in said ears is a lever 12, one arm 13 of which extends beyond the standard and overhangs a portion of the base, the other arm 14 overhanging a platform 15 formed upon the standard. This 40 platform is provided with a suitable seat 16 to receive a vise or clamping die 17 and the arm 14 of the lever is provided with a corresponding seat 18 carrying a coacting die 19. Coacting cutting or shaping dies 45 20 may also be mounted on the lever arm 14 and platform 15, as will be readily understood by those skilled in the art.

The free end of the arm 13 of the lever 12 is disposed above a vertical cylinder 21 located on the base 8 at one side of the stand-

ard 10, and in this cylinder is arranged a reciprocating piston 22 to which is connected a piston rod 23 having a connection 24 with the free end of the lever 13. The weight of the piston 22, the piston rod 23 and the arm 13 of the lever is greater than the other arm 14 with the parts carried thereby, so that the normal position of the parts is as illustrated in Fig. 2.

Extending rearwardly from the upper portion of the standard 10 is a horizontal rod 25 having a reduced stem 26 that slidably passes through said standard and has a nut 27 threaded upon its free end. Adjustably mounted on this rod 25 by means of a suitable clamp 28, is a pneumatic hammer preferably of the valveless type, and comprising a cylinder 29 within which operates a piston 30. It is believed to be unnecessary to describe the structure and operation of this hammer in detail. Mounted upon the end thereof, adjacent to the standard 10, and thus interposed between said hammer and the stem, is a dolly carrier comprising a sleeve 31, said sleeve having a bore 32 and an enlarged chamber 33 in its rear portion. A dolly 34 is slidably mounted in the holder and has a head 35 co-operating with the vise, or in other words, so disposed that it will operate on a drill bit 36 clamped in said vise. The rear portion of the dolly projects into the chamber 33 and has an abutment flange 36 arranged to engage a stop 37 located in the chamber 33. A piston bore 38 is formed in the dolly 39 holder at one side of the bore 32, and operating therein is a piston 39 that bears against the abutment 36 on the side opposite to that which engages the stop.

A portion of the supply pipe for the motive fluid is shown at 40, and leads from any suitable source. This supply pipe has connected thereto a branch 41 that in turn is connected to the dolly holder 31 and is in communication with the piston bore 38 through a suitable channel 42. Thus it will be seen that fluid is constantly in the bore 38, and by forcing the piston 39 rearwardly serves to normally maintain the dolly 34 in its rearmost position. However, the dolly 45 when struck by the hammer piston 30 will operate against the piston 39, and be driven forwardly.

The supply pipe 40 is connected with a casing 43 in which a plunger valve 44 oper-

ates. The casing 43 is provided with a lower internal annular channel 45 with which the supply pipe 40 communicates, an intermediate channel 46 with which a pipe 47 leading to the cylinder 21, communicates, another channel 48 above the channel 46 from which a pipe 49 extends to the dolly hammer 29 and an uppermost channel 50 having an exhaust nipple 51 in communication therewith. The valve 44 comprises a neck 52 with spaced heads 53 thereon located constantly on opposite sides of the motive fluid supply channel 45, and the upper end of the valve has a link connection 54 with the crank arm 55 of a rock shaft 56. This shaft is journaled in the rear side of the standard 10 as shown at 57, and has a handle crank 58 at one end, in convenient reach of the operator. A coiled spring 59 surrounding the shaft and connected thereto as illustrated at 60 bears against the adjacent journal box 57 and acts to frictionally hold the valve 44 in any desired position. The movement of said shaft is limited by a pin 61 operating in a cut away portion 62 of one of the journal boxes 57.

It is believed that the operation of the apparatus will be readily understood by those skilled in the art. With the parts as shown in the drawings, the apparatus is at a standstill. If now a tool to be operated upon is introduced into the vise between the dies 17 and 19 and the handle crank is turned rearwardly, the piston valve 44 will be moved upwardly. It will be recalled that the fluid under pressure is in the lowermost channel 45 of the valve casing 43 and as the valve 44 moves upwardly the upper head 53 thereof will cross the next channel 46. This will bring said channel into communication with the channel 45, and consequently the fluid will pass through the pipe 47 into the lower end of the cylinder 21, the piston 22 therein will be elevated, and the lever 12 swung to close the jaws or dies 17 and 19 upon the tool. A further upward movement of the valve 44 carries the upper head 53 above the channel 48, so that motive fluid from the channel 45 can then also pass through the pipe 49 to the dolly hammer 29 and cause the actuation thereof. The valve 44 is then in its uppermost position and the vise and dolly hammer are both in operation. Upon a retrograde or downward movement of the valve 44 the upper head 53 will pass below the channel 48, thereby first cutting off the supply of motive fluid to the dolly hammer 29 and then opening it to the exhaust channel 50 and nipple 51. A further downward movement in like manner cuts off the fluid supply from the vise cylinder 22 and also opens said cylinder to the exhaust channel 50, whereupon the piston 22 will drop to its own weight and the vise jaws thus be opened.

From the foregoing, it is thought that the construction, operation and many advantages of the herein described invention will be apparent to those skilled in the art, without further description, and it will be understood that various changes in the size, shape, proportion, and minor details of construction, may be resorted to without departing from the scope of the invention as defined by the claims.

Having thus fully described my invention, what I claim as new, and desire to secure by Letters Patent, is:—

1. In apparatus of the character set forth, the combination with a base and a standard rising therefrom, of a vise on the standard including a lever fulcrumed on the standard and having a jaw on one arm thereof, a motor for the lever connected to the other arm of the vise and mounted on the base alongside the standard, a shaping hammer mounted in coacting relation to the vise, means for supplying motive fluid to the motor and hammer, and means for controlling the motive fluid supply to cause the operations of the vise and hammer in succession.

2. In apparatus of the character set forth, the combination with a base and a standard rising therefrom, of a vise mounted on the standard including a lower stationary jaw and a lever pivoted on the standard and having an upper movable jaw in coaction with the lower jaw, said lever extending beyond the standard over the base, an upright cylinder mounted on the base alongside the standard, a piston in the cylinder having a connection with the overhanging portion of the lever, and a hammer co-operating with the vise.

3. In apparatus of the character set forth, the combination with a vise, of a hammer, mechanism for operating the vise and hammer, a dolly holder mounted on the hammer and interposed between the hammer and the vise, a dolly slidably mounted in the holder, and a piston in the dolly holder engaged with the dolly.

4. In apparatus of the character set forth, the combination with a vise, of a hammer, mechanism for operating the vise and hammer, a dolly holder mounted on the hammer and having an internal stop, a dolly slidable in the holder and having a projection, one side of which abuts against the stop, and a piston in the holder bearing against the opposite side of the projection to urge the dolly rearwardly against said stop.

5. In apparatus of the character set forth, the combination with a vise, of fluid operated actuating means therefor, a fluid operated dolly hammer, means for supplying fluid to the actuating means and hammer, including a piston valve casing having a supply port, an exhaust port spaced from

the supply port and distributing ports located between the supply and exhaust ports and respectively communicating with the vise actuating means and dolly hammer, 5 and a piston valve operating in the casing and movable therein to a position to cut off the supply from both distributing ports while leaving both of said distributing ports in communication with the exhaust port and 10 also movable to a position to cut off the exhaust port from both distributing ports while leaving the said distributing ports in communication with said supply port.

6. In apparatus of the character set forth, 15 the combination with a vise, of fluid operated actuating means therefor, a fluid operated dolly hammer, means for supplying fluid to the actuating means and hammer, including a piston valve casing having a 20 supply port at one end portion, an exhaust port at the other end portion, and distributing ports located at spaced points between the supply and exhaust ports and respectively communicating with the vise actuating 25 means and dolly hammer, and a piston valve operating in the casing and including a head movable from a position between the supply port and distributing ports to a posi-

tion between the exhaust port and distributing ports and vice versa, and during such 30 movement crossing the distributing ports successively.

7. In apparatus of the character set forth, the combination with a vise including a support, of a laterally projecting rod having a 35 reduced stem secured in the vise support, and a dolly hammer mounted on the rod and coöperating with the vise.

8. In apparatus of the character set forth, the combination with a vise including a support having a transverse opening there-through, of a laterally projecting rod having a reduced stem extending through the opening and having a shoulder abutted against the support, a fastening device on 45 the stem and coöperating with the opposite side of the vise to that abutted against by the shoulder, and a dolly hammer mounted on the rod and coöperating with the vise.

In testimony whereof, I affix my signature 50 in the presence of two witnesses.

WILLIAM A. SMITH.
